UNITED STATES PATENT OFFICE.

SILAS CONSTANT, OF BROOKLYN, NEW YORK.

IMPROVEMENT IN ROSIN-OIL LAMPS.

Specification forming part of Letters Patent No. 10,443, dated January 24, 1854.

To all whom it may concern:

Be it known that I, SILAS CONSTANT, of Brooklyn, in the county of Kings and State of New York, have invented a new and Improved Rosin-Oil Lamp; and I do hereby declare that the following is a full and exact description thereof, reference being had to the accompanying drawings, making a part of this specification—

Figure 1 being a vertical central section; Fig. 2, a side view of a portion of the lamp detached; Fig. 3, a transverse section in the line *a a* of Fig. 1, and Fig. 4 a section in the line *b b* of the same figure.

Similar letters indicate like parts in all the figures.

My rosin-oil lamp has the following improvements which distinguish it from all other lamps: First, it has a tube *g*, combined with and inclosing the guide or slotted tube *f* in such a manner as to produce a narrow annular space between the two for the purpose of causing the oil to rise in said space by the effects of capillary attraction and the heat thrown into the same from the burner to such a height as to keep the elevated upper end of the wick fully supplied with oil so long as any oil remains in contact with the lower half of the wick.

My second improvement consists in inclosing the portion of the wick which rises above its guide *f* with a perforated conical tube *m*, which ascends to the top of the wick, or nearly so, and with its upper extremity brought nearly or loosely in contact with the periphery of the wick, where it is for the purpose of conducting air into the wick in an uncompressed state as one of the elements of furnishing the requisite quantity of oxygen for burning rosin-oil.

My third improvement consists in locating and securing a draft-tube *c* centrally within the burner *d* and combining with the said draft-tube the ordinary button *b* and a perforated and deflecting head *a*, placed immediately above said button, for the purpose of dividing the air that enters the oil-cup *Q*, causing a part to rise in the burner to be discharged under the button *b* upon the top of the wick in the usual manner and the remainder to rise into the head *a* and be discharged therefrom in a heated state into the flame of the lamp, the effect of which will be to produce

a more intensely white flame and to consume any smoke that might rise with the flame, and also prevent sudden gusts of air into the oil-cup from producing great deviations in the magnitude of the flame or causing smoke and flame to rise to the top of the chimney, as is the case with other lamps.

My fourth improvement consists in a lip *k*, projecting downward from the under side of the perforated cap *II*, which supports the chimney, said lip being located within the series of air-holes *o o* for the purpose of preventing the air as it enters the air-chamber below said cap from passing directly into the annular space between the inner cap *m* and the tapering or conical tube *v*, which rises from said cap, and thereby forming another safeguard against the injurious effects produced by gusts of wind upon my improved lamp.

The body of my rosin-oil-lamp, the perforated oil-cup below the same, and the burner or tube *d* do not essentially differ from the lamp generally known as the "solar lamp," save that the burner of my lamp is somewhat larger, and its upper end is elevated above the body of the lamp. The guide or slotted and perforated tube *f*, which incloses the wick in the solar lamp, is combined directly with the concave inner cover *G*, placed within and resting upon the top of the body of the lamp; but in my rosin-oil lamp the tube *g* is combined with the said cover *G*, and the guide *f* is combined with the said tube *g* in such a manner as to form a narrow annular space *t* between the two, as shown in Fig. 1. The object of the said annular space *t* is to compel the oil to rise in the wick higher than it would otherwise do, and thereby cause the lamp to burn more brightly and until the oil is nearly all consumed in the lamp. The tube *g* rises a short distance above its junction with the inner cap *G* and receives upon its upper end the conical tube *m*, the said tube fitting thereon with sufficient closeness and accuracy to be kept securely in its proper position with relation to the wick. I shall generally make said conical tube *m* of such a size that at its upper end there will be a very slight space between it and the wick; but it may be brought lightly in contact with the wick. The draft-tube *c* may be supported by a transverse ring *l*, as represented in the draw-

ings, or in any other proper manner. The perforations in the head *a*, which surmounts the tube *c*, may be in its extreme periphery or in its under inclined deflecting-surface. I prefer, however, the latter position. Air is admitted to the chamber situated between the covers *G* and *H* through one or more series of apertures *o o* beyond the base of the chimney. As the air enters said chamber it is prevented from rushing directly into the annular conical space between *v* and *m* by the descending lip *k*, which prevents gusts of air from being forced through said space up the chimney, which would cause great deviation in the amount of flame and temporarily produce smoke. A portion of air will pass from said chamber through the apertures *n n* into the conical tube *m* and penetrate the wick in its then uncompressed state, and also pass up in and around the same to the flame. The apertures *p p* in the inner cap *G* give the air free access to the surface of the oil in the lamp.

My improvements in lamps to adapt them to the burning of rosin-oil may be applied to new or to old lamps in any manner that may be deemed best, as I do not intend to limit their application to any special and precise

mechanical arrangement, provided their principle of action be embodied.

What I claim as my invention, and desire to secure by Letters Patent, is—

1. Inclosing the portion of the wick which rises above its guide within a perforated conical tube *m* for the purpose of causing a portion of the air that enters the chamber between *G* and *H* to be brought in contact with the wick which is then in an uncompressed state and to rise in and about the same to the flame, substantially as herein set forth.

2. The draft-tube *c*, placed within the burner and having the button *b*, and the perforated and deflecting head *a*, combined therewith, substantially in the manner and for the purpose herein set forth.

3. The lip *k*, projecting downward from the under side of the cap *H* within the series of air-holes in the same for the purpose of preventing gusts of air from producing puffs of smoke up the chimney, substantially as herein set forth.

SILAS CONSTANT.
